UNITED STATES PATENT OFFICE

2,449,576

VISIBLE INDEX SIGNAL MEANS

Charles E. Attwood, Chicago, Ill., assignor to
Acme Visible Records, Inc., Chicago, Ill., a cor-
poration of Delaware

Application August 25, 1944, Serial No. 551,114

3 Claims. (Cl. 129—16.7)

1

This invention relates to visible index record devices and particularly to novel signalling means for use and in combination therewith.

The present invention relates in general to signalling means employed in connection with record card holders of the class having a transparent sheath embracing the lower marginal edge portion of the holder, known as pocket-type holders, and which are adapted to support record cards with the lower marginal edge portions of the card projected within the sheath or pocket. These card holders, as conventional, are adapted to be hingedly mounted on trays or holders in overlapping relationship with the lower marginal portions of the cards visible through the transparent sheaths, and the visible margins of the cards are conventionally provided with imprinted index data or with delineated areas for insertion of such data, and thereby provide a visible index component or area for the record cards. This visible index component may, as indicated, be the lower marginal edge portion of the record card, or in the alternative an integral upturned lip, or a separate index insert.

It has further been conventional to employ in combination with such visible index components signalling means in the form of movable or slideable strips or pieces of transparent material of a contrasting color to the record card or its visible index component for the purpose of directing attention to specific conditions, periods, amounts and the like. However, by reason of the fact that such signals are slideable or movable they are subject to accidental movements in the handling and use of the overlapping holders. In practice it has been found that most of the signalling means at present used are so likely to become dislodged that after entering the conditions indicated on the visible line the lifting up of the card is usually necessary to determine whether the condition indicated on the visible margin is correct. Thus instead of providing dependable, positive signalling means, the prior devices have provided more or less guides which generally had to be checked.

In accordance with the present invention dependable and positive signalling means are provided and wherein the signal or position of the signal or condition which it indicates is positive and locked and cannot be disturbed in the continuous lifting over and manipulation of the cards for posting purposes or accidental displacement by the cuff of the user.

The signalling means of the present invention

5 further permits the entire length of the visible margin to be used to indicate progress, interrupted progress or block signalling and one signal can be used for any adaptation of any of such purposes.

10 The present invention comprises the employment of the card holder having a transparent sheath embracing the lower marginal edge portion thereof with a record card supported on the holder with the lower marginal edge portion, comprising an index area component thereof, extended within the pocket or sheath of the holder, the index portion of the card being formed with a plurality of downwardly projecting tongues, or 15 formed with a series of vertical slots extending to the lower marginal edge dividing it thereat into a plurality of tongues, and an elongated strip of contrasting color to the card extending across and engaged within the sheath, the 20 tongues being adapted to be severally positioned, within said sheath, in overlying and underlying relationship to the elongated colored strip for signalling cooperation therewith.

25 The slotting at the bottom of the card, which can be done to accommodate any number of conditions or stations, forms a simple, compact, and economical means of accomplishing many different varieties of signalling. Once a signal strip is inserted within the pocket of the holder, which 30 can be done at the factory, the user or customer is relieved of all other requirements in placing the signal except the manipulation of the card. When the card is removed for any reason from the pocket there is no danger of the signal strip falling out.

35 The invention will be further described in connection with the following specification and accompanying drawings wherein:

40 Fig. 1 is a face view of a record card wherein the lower marginal edge or index portion thereof is divided by a series of slots extending to the edge thereof dividing it into a plurality of tongues.

45 Fig. 2 is a face view of a record card holder of the pocket type having an elongated colored signal strip engaged within the pocket thereof and having mounted thereon the card of Fig. 1.

50 Fig. 3 is a face view of the elongated colored signal strip employed in the pocket of the holder of Fig. 2.

Fig. 4 is a fragmentary view with parts broken away of the lower marginal edge portion of a card holder embodying the signal means of my invention similar to that of Figs. 1 to 3, illustrating one method of signalling use thereof.

Fig. 5 is a view similar to that of Fig. 4 further

3

illustrating the method of signalling use of my invention.

Fig. 6 is also a view similar to those of Figs. 4 and 5 and further illustrating signalling use of my invention.

Fig. 7 is an enlarged section on the line 7—7 of Fig. 2.

Fig. 8 is an enlarged section taken on the line 8—8 of Fig. 5.

Fig. 9 is an enlarged section taken on the line 9—9 of Fig. 5.

Referring to the drawings, reference numeral 25 indicates a card holder of the conventional type having a transparent sheath 26 embracing the lower marginal edge portion thereof and engaged thereto by means of a pair of staples 27. The holder 25 is adapted to support record cards by engaging the upper corners of the record card through the oblique slots 28 in the body of the holder and by extending the lower marginal edge portion of the card within the sheath 26, the lower marginal edge portion of the card being visible through the transparent sheath 26.

The card holders 25 are provided with flexible hinge lines such as defined by the lines of perforations 29 and the holder is secured to a suitable mounting means or hanger strip 30, whereby a plurality of such holders may be mounted against the surface of a suitable tray or other holder, with the card holders in overlapping relationship to each other, and spaced longitudinally of the tray so as to expose the sheathed portion of each card holder and to thereby permit the lower marginal edge portion of a supported card to provide visible indexing means.

In accordance with the form of the present invention illustrated in Figs. 1 to 9, signalling means are provided for use and in combination with the visible index area of the record card by positioning an elongated strip 31, composed preferably of a transparent flexible plastic material such as for example Celluloid, and of a contrasting color to that of the record card to be mounted on the holder. This signal strip 31 is of a length which extends substantially completely across the width of the holder and is engaged within the pocket by means of the lateral projections 32 which are adapted to enter the sheath 26 beneath the edge of the staples 27 and to thereby hold the signal strip 31 against accidental upward withdrawal or displacement.

For signalling purposes in combination with the signal strip 31, record cards 33 which are otherwise of conventional shape and size are employed wherein, however, in accordance with the present invention, the lower marginal index edge area component portion generally indicated as 34 is divided into a horizontal series of downwardly depending tongues 35 by means of the slots or slits 36 extending to the lower marginal edge of the card 33.

The index area 34 of the card 33 may be thus divided into any desired number of tongues such as for example twelve when it is desired that the divisions be for the months of the year, as indicated at 37, or the alternative, the division may be made for any other suitable purpose desired such as for example ten divisions or tongues for numbering purposes by commodities, etc.

Fig. 2 illustrates a holder 25 having a card 33 supported thereon with the lower marginal edge portion or divided index area component thereof extended within the transparent sheath 26, this divided index area portion being superimposed over the elongated signalling strip 31 seated

4

within the pocket and engaged therein by means of its lateral projections 32.

The arrangement of the component parts as illustrated in Fig. 2 may be considered to be the initial condition when no signalling is indicated. In signalling use one or more of the tongues 35 are extended over the upper edge of the strip 31 and positioned rearwardly thereof, that is, between the signal strip and the body of the holder 25 to thereby leave exposed or superimposed a section of the colored strip 31 over a tongue 35. Conversely, contrast may be brought about by initially superimposing the full length of the colored strip 31 over the face of the lower marginal edge index area component 34 of the card 33 and thereafter for signalling purposes one or more of the tongues 35 brought forwardly over the upper edge of the strip 31 and positioned between the strip 31 and the sheath 26 to thereby provide contrast in color.

Figs. 4, 5 and 6 are illustrative of the use of the present invention wherein initially the card and the colored signal strip are initially in the positions indicated in Fig. 2. Thus, for example, Fig. 6 shows a regular succession of tongues 35 extended beneath the colored signalling strip 31 for the purpose of indicating a uniformly progressive condition by months. The illustration in Fig. 5 in a similar manner illustrates a plurality of tongues projecting rearwardly of the colored signal strip 31, an arrangement which may be indicative of interrupted progress, that is, certain intervening tongues still remain forwardly of the colored signal strip 31.

Fig. 4 illustrates what may be considered a multiple block signal, that is, an isolated number of tongues have been projected rearwardly of the colored signal strip 31 to direct attention to, for example, particular months.

From the foregoing it will be obvious that the various arrangements and signal combinations may be employed for the purpose of indicating various conditions and in various single and multiple arrangement and, of course, as previously indicated, the depending series of tongues may be of any desired predetermined number and may bear predetermined index data or such data may be inscribed on the tongues to suit any desired purpose or arrangement. Once, however, signal strip 31 is inserted within the transparent sheath 26 and engaged therein by means of the lateral extensions 32, the only requirement of the user is to position the tongues 35 in desired relationship to the signal strip 31, which arrangement cannot be disturbed in the lifting and manipulation of the holders during use of the cards for posting or reference purposes, and when a card is removed for any reason from the pocket there is no danger of signal strip 31 falling out.

While this invention has been shown but in one form, it is obvious to those skilled in the art that it is not so limited but is susceptible of various changes and modifications without departing from the spirit and scope of the claimed invention.

I claim as my invention:

1. A visible index record device comprising a card holder, a transparent sheath embracing the lower marginal edge portion of said card holder, a record card supported on said holder and extending within said sheath, an elongated signal strip of contrasting color to said card extending within the sheath, and means to secure said signal strips against displacement from said

sheath the lower portion of said record card being formed with a plurality of downwardly projecting tongues severally adapted to be positioned in overlying or underlying relationship to said signal strip for signalling cooperation therewith.

2. A visible index record device comprising a card holder, a transparent sheath embracing the lower marginal edge portion of said card holder, a record card supported on said holder with the lower edge portion thereof projected within said sheath, an elongated signal strip extending across the width of the holder and engaged within and projecting freely above said sheath thereof, and means provided on said card holder to prevent upward or lateral displacement of said signal strip, said signal strip being colored in contrast to the color of said card, and the lower marginal edge portion of said card being in the form of a plurality of downwardly projecting tongues, said tongues being adapted to be positioned forwardly or rearwardly of the colored strip for signalling purposes.

3. A visible index record device comprising a card holder, a transparent sheath embracing the lower marginal edge portion of said card holder, a record card supported on said holder with the

lower marginal edge portion comprising an index area component thereof extended within said sheath, an elongated strip of contrasting color to said card extending across and engaged within said sheath, and staples provided at the sides of said card holder to prevent displacement of said elongated strip from said sheath, said index portion of the record card being formed with a series of vertical slots extending to the lower marginal edge dividing it into a plurality of tongues, said tongues being adapted to be severally positioned within said sheath in overlying or underlying relationship to said elongated strip for signalling cooperation therewith.

CHARLES E. ATTWOOD.
